US00D782024S

(12) **United States Design Patent** (10) **Patent No.:** **US D782,024 S**
(45) **Date of Patent:** **** Mar. 21, 2017**

(54) **VENT CLIP**

(71) Applicant: **Griffin Technology, LLC**, Irvine, CA (US)

(72) Inventor: **Jennifer Ann Murphy**, Nashville, TN (US)

(73) Assignee: **Griffin Technology, LLC**, Irvine, CA (US)

(**) Term: **14 Years**

(21) Appl. No.: **29/514,417**

(22) Filed: **Jan. 13, 2015**

(51) LOC (10) Cl. **23-04**

(52) U.S. Cl.

USPC **D23/393**

(57)

CLAIM

The ornamental design for a vent clip, as shown and described.

DESCRIPTION

FIG. 1 is a front perspective view of the new design for a vent clip;

FIG. 2 is a back perspective view of the new design for a vent clip;

FIG. 3 is a top plan view of the vent clip;

FIG. 4 is a left elevation view of the vent clip;

FIG. 5 is a front elevation view of the vent clip;

FIG. 6 is a bottom plan view of the vent clip;

FIG. 7 is a right elevation view of the vent clip; and,

FIG. 8 is a back elevation view of the vent clip.

The dashed line surface shading illustrates surface contours of the claimed design and said lines form no part of the claimed design.

1 Claim, 3 Drawing Sheets
